ROTARY DUPLICATOR

Leo Kluitmann, Dusseldorf, Germany

Application January 17, 1935, Serial No. 2,185
In Germany August 10, 1931

5 Claims. (Cl. 101—132)

This invention relates to a device for printing on sheets.

It has been proposed already to change the form in duplicating machines automatically without stopping the machine by actuating a lever, etc. for moving the form resting on a feeding table towards the printing drum to bring it within ranges of a gripping device secured to the drum. By means of a cam, a lever arm arranged on the printing drum is controlled to open the gripping device during the same operation, so that the previously fixed form drops out and the new form is held on the drum after the lever arm has passed the cam.

According to the invention, the control of the device for changing the form is to be effected automatically after a certain number of copies have been made. It is known to print a plate or stencil in addressing machines several times and then to change it automatically, but these known devices are, as a rule, required to reprint only a very limited number of addresses and are not suited for duplicators, in which the form has to be changed only after a larger number of copies have been printed, which fluctuates considerably. Furthermore, the changing of paper forms in duplicators differs essentially from changing stencils in addressing machines.

According to the invention, the change is effected by means of a rack which at each rotation of the printing drum is moved by a tooth rotating with the drum. This is continued until a rider adjusted on the rack moves a two-armed stop lever securing a spring-urged second lever for the automatic change of the original out of normal position and thus releases the automatic change of the original. The rack then automatically returns to initial position, and the lever for releasing the change of the original is returned to securing position. This is effected by a control cam rotating with the drum and a slide roll which bring the lever controlling the change of the original back to operating position, whereupon after engagement of the locking mechanism the stop lever controlled by the rider is secured by a spring.

By way of example, the invention is illustrated in one embodiment in the accompanying drawings, in which Figure 1 is a side view of the device; Fig. 2, a section of Fig. 1 with the toothed disc removed shortly before the pressing back of the hand lever; and Fig. 3, a partial top view.

Referring to the drawings, a rack 1 is slidably mounted in its longitudinal direction in guides 18 which are secured to the machine frame 13.

The rack 1 carries on its toothed part a rider 2 which is adjustable in the longitudinal direction of the rack 1. The rear end of the rack 1 is connected with the end of a spring 9 which in the represented embodiment is a spiral plate spring or drum spring as it is used in type-writing machines and which has the advantage that it may be widely extended and needs only a minimum of space. The spring 9 is mounted on a pin or screw bolt 31 secured to a bracket 30 of the machine frame. At each rotation of the printing drum 21 the rack 1 is displaced step by step by the tooth 3 rotating with the drum 21 and engaging each time the toothed part of the rack. The pawl 4 pivotally mounted on the machine frame holds the rack 1 in the position attained by means of the tooth 3 against the pull of the spring 9. A control lever 5 is pivotally mounted on a pin 14 in the side wall 13 of the machine frame and provided with a spring 7 at its one end, the said spring being secured at 36 to the machine frame. Near the said end of the lever 5 a pin 5a is arranged. A stop lever 6 pivotally mounted on the machine frame and provided with a nose 6a is held in engagement with the pin 5a of the control lever 5 and against an abutment pin 37 of the machine frame by means of a spring 12 secured at 29 to the machine frame. The lower end of the said stop lever lies in the path of the rider 2 of the rack 1. After the drum 21 has made the number of revolutions fixed by the adjustment of the rider 2 the latter abuts the stop lever 6 and moves the same about its pivot 38, so that the nose 6a of the stop lever 6 releases the pin 5a of the lever 5 and the spring 7 moves the latter about its pivot 14.

The control lever 5 is connected by a pin 23 with a slide 25. The slide 25 is embedded in a guide or carriage 24 connected with the side wall 13 and carries a cam disc 26 which is lifted when the lever 5 is swung out whereby at the rotation of the drum 21 a lever arm 27 is raised. The lever arm 27 is positioned on a shaft 22 in the drum 21, which carries the grippers 28 for holding the form. Owing to this operation, the grippers 28 extending through the circumference of the drum are opened, the form hitherto fixed on the drum 21 is thus released after the grippers 28 have passed the lowermost point of the drum 21 and drops onto a delivery table 35 which is arranged on the machine frame.

The new form which is to be clamped is laid upon a feeding table 20 which is pivotally supported by a rod 32, which in its turn is pivotally mounted at 34 on the machine frame, and further

supported by a pin 15 arranged on the lever 5. Simultaneously with the motion of the lever 5 the pin 15 is lowered, whereby the front portion of the table 20 is moved by the springs 18 towards the drum 21. In the meantime, the drum 21 has continued to rotate, so that the grippers 28 extending over the circumference thereof in opening position have slipped under the front edge of the form to be fixed on the circumference of the drum 21. The table 20, by means of the pins 17 arranged on the drum 21 and the noses 16, is then drawn in the direction of rotation of the drum 21 until the opened grippers 28, owing to the sliding off of the lever arm 27 from the cam disc 26, close again and thus fix or hold the form positioned within range of the grippers 28.

When the lever 5 is drawn by the spring 7, the pawl 4 is lifted out of range of the teeth of the rack 1 by a rod 8 pivotally connected with the lever 5 and the pawl 4. The released rack 1 is then returned to initial position by the spring 9. After the spring 7 has acted upon the lever 5 the eccentrically disposed disc 10 which in normal position of the lever 5 freely rotates with the drum 21 passes over the slide roll 11 of the lever 5 and brings the latter back to initial position. Then the spring 12 draws the stop lever 6 into normal position, so that the lever 5 is secured by the nose 6a of the lever 6 and the pin 5a. The lever 5 remains in normal position until the process described is repeated.

What I claim and desire to secure by Letters Patent of the United States is:

1. In a rotary duplicator for printing on sheets a device for controlling the change of the form after a predetermined number of copies, comprising a rotatable printing drum, means for automatically changing the form, a movable rack, a rider adjustable on said rack, a stop lever operatively connected with the means for changing the form, and a control projection connected with said drum and being capable to rotate with the same, the said control projection being arranged so as to displace said rack step by step at each rotation of said drum until the rider adjustable on the rack releases by means of said stop lever the means for automatically changing the form.

2. In a rotary duplicator for printing on sheets a device for controlling the change of the form after a predetermined number of copies, comprising a rotatable printing drum, means for automatically changing the form, a movable rack, a rider adjustable on said rack, a lever controlling the means for changing the form, a stop lever engaging the said controlling lever, spring means secured to one end of said rack, a pawl locking the rack, a rod pivotally connected with the said pawl and the said controlling lever, and a control tooth connected with the said drum and capable to rotate with the same, the said control tooth being arranged so as to displace said rack step by step at each rotation of said drum until the said rider releases by means of said stop lever the lever controlling the means for changing the form, whereas the said pawl, rod and controlling lever being arranged and interconnected so that at the motion of the stop lever by the rider releasing the controlling lever the said pawl is lifted out of the rack and the latter is returned to zero position by the said spring, while the controlling lever is brought again in its initial position by means of the said control cam and slide roll.

3. In a rotary duplicating machine for printing on sheets a device for automatically controlling the change of the form after a predetermined number of copies, comprising a machine frame,

a printing drum rotatably mounted in the machine frame, means for automatically changing the form, a longitudinally slidable rack, a rider adjustable on said rack, a spring secured to one end of the rack, a pawl locking the rack, a lever controlling the means for changing the form, a two-armed stop lever disposed in the machine frame, one arm of the said stop lever being fitted with a nose whereas the other arm of the stop lever is positioned in the path of the rider, a pin 10 on the said controlling lever adapted to engage the said nose of the stop lever, a rod pivotally connected with the said controlling lever and the said pawl, and a control tooth connected with the said drum and adapted to rotate with the same, the said control tooth being arranged so as to displace said rack step by step at each rotation of said drum until the said rider releases by means of said stop lever the lever controlling the means for changing the form, whereas the said pawl, rod and controlling lever being arranged and interconnected so that at the motion of the stop lever by the rider releasing the controlling lever the said pawl is lifted out of the rack and the latter is returned to zero position by the said 25 spring.

4. In a rotary duplicating machine for printing on sheets a device for automatically controlling the change of the form after a predetermined number of copies, comprising a machine frame, a printing drum rotatably mounted in the machine frame, means for automatically changing the form, a longitudinally slidable rack, a rider adjustable on said rack, a spring secured to one end of the rack, a pawl locking the rack, a lever 35 controlling the means for changing the form, a two-armed stop lever disposed in the machine frame, one arm of the said stop lever being fitted with a nose whereas the other arm of the stop lever is positioned in the path of the rider, a pin 40 on the said controlling lever adapted to engage the said nose of the stop lever, a spring secured to the stop lever for holding the nose of the same in engagement with the said pin of the controlling lever, a rod pivotally connected with the said 45 controlling lever and the said pawl, a control cam connected to the said drum and adapted to rotate with the same, a slide roll mounted on the said controlling lever and adapted to engage with the said control cam, and a control tooth rotatable 50 with the said drum, the said control tooth being arranged so as to displace said rack step by step at each rotation of said drum until the said rider releases by means of said stop lever the lever controlling the means for changing the form, whereas 55 the said pawl, rod and controlling lever being arranged and interconnected so that at the motion of the stop lever by the rider releasing the controlling lever the said pawl is lifted out of the rack and the latter is returned to zero position by the 60 said spring, while the controlling lever is brought again in its initial position by means of the said control cam and slide roll.

5. In a rotary duplicating machine for printing on sheets a device for automatically controlling the change of the form after a predetermined number of copies, comprising a machine frame, a rotatable printing drum mounted in the machine frame, a table for feeding the form pivotally mounted on the machine 70 frame, a lever for controlling the change of the form being pivotally mounted on the said frame, a pin on the controlling lever for supporting the feeding table, spring means connected with the feeding table for pressing the 75

same down on the supporting pin of the controlling lever so that when the latter is lowered the feeding table approaches the said drum, a rotatable shaft on the drum, grippers for holding the 5 form, the said grippers being arranged on the said shaft and extending through the circumference of the drum, a lever arm secured on the said shaft, a slide roll on the said lever arm, a carriage on the machine frame, a slide embedded 10 in the said carriage and guided by the same, a cam disc disposed on the slide, a pin arranged on the slide, an opening in the said controlling lever for engaging with the said pin of the slide so that the slide and its disc cam may be 15 lifted together with the controlling lever whereby the said cam disc is brought in the path of the lever arm and slide roll so as to lift the same and the grippers and release the clamped form, noses on the said feeding table, pins arranged 20 on the drum adapted to engage with the said noses of the feeding table when the latter is lowered so as to withdraw the feeding table in the direction of rotation of the drum a longitudinally slidable rack, a rider adjustable on the 25 rack, a spring secured to one end of the rack, a pawl locking the rack, a two-armed stop lever disposed on the machine frame, one arm of the

5 said stop lever being fitted with a nose whereas the other arm is positioned in the path of the rider, a pin on the said controlling lever adapted to engage the said nose of the stop lever, a spring secured to the stop lever for holding the nose of the same in engagement with the said pin of the controlling lever, a rod pivotally connected with the said controlling lever and the said pawl, a control cam connected to the said drum and adapted to rotate with the same, a slide 10 roll mounted on the said controlling lever and adapted to engage with the said control cam, and a control tooth rotatable with the said drum, the said control tooth being arranged so as to displace said rack step by step at each rotation 15 of said drum until the said rider releases by means of said stop lever the lever controlling the means for changing the form, whereas the said pawl, rod and controlling lever being arranged and interconnected so that at the motion 20 of the stop lever by the rider releasing the controlling lever the said pawl is lifted out of the rack and the latter is returned to zero position by the said spring, while the controlling lever is brought again in its initial position by means 25 of the said control cam and slide roll.

LEO KLUITMANN.
